UNITED STATES PATENT OFFICE.

ZELTON D. BRUMBERG, OF IRONTON, OHIO.

DISPLAY DEVICE.

Application filed May 6, 1926. Serial No. 107,186.

My present invention has to do with the advantageous display of merchandise and it contemplates the provision of a peculiar and advantageous device whereby merchandise 5 may be displayed to advantage in such manner that floor space is economized.

The invention also contemplates the provision of a device whereby dry goods in the piece, preferably bolt goods may be displayed to good advantage and this while 10 economizing in space, the bolt formation of the goods being utilized for the quick and convenient securing of the goods, and the end portions of the goods in the several bolts 15 being draped so as to display the characteristics of the goods in substantially the same manner as would be the case were the goods incorporated in dresses.

With the foregoing in mind, the invention 20 consists in the improvement as hereinafter described and definitely claimed.

In the accompanying drawings, forming part of this specification:—

Figure 1 is a side elevation illustrating in 25 use the bolt-goods display embodiment of my invention.

Figure 2 is a top plan view of the display device per se.

Figure 3 is an end elevation of the display 30 device per se.

Similar numerals of reference designate corresponding parts in all of the views of the drawings.

Among other elements my improvement 35 comprises an appropriate support 1, the said support being preferably, though not necessarily, in the form of a table top superimposed on and supported by legs as 2.

In addition to the support 1, the illustrated and preferred embodiment of my invention comprises two end uprights 3, preferably of wood, and a plurality of transverse series of uprights 4 spaced from the uprights 3 and also spaced apart and arranged 45 with the uprights in each series spaced from the other uprights on the series as appears in Figure 2. It will also be noticed that the side uprights of each series transversely of the support 1 are comparatively short, that the intermediate uprights of each transverse 50 series are comparatively long, and that the center upright of each transverse series is of a greater length than the other uprights in the series, Figure 3.

The uprights 3 and 4 are in the form of blades, and said blades are tapered or grad-

ually reduced in thickness upwardly and hence it will be understood that each blade is adapted to readily penetrate between the inner layer of a piece of goods in a bolt and the cardboard of the bolt, and hence when a bolt of goods is impaled on one of the blades as shown in Figure 1, the blade resting between the cardboard of the bolt and the innermost coil about the board will serve 60 efficiently in maintaining the bolt of goods in upright position and in such state that an end portion may be unwound from the bolt and draped in a pendent or other appropriate manner so as to display to excellent 65 advantage the goods in the bolt, and this under practically the same conditions as obtains when the goods is incorporated in a skirt or other garment. It will also be 70 manifest that the goods impaled upon the innermost or central blade 4 of each transverse series will extend above the other goods and that the goods impaled on the intermediate blades of each transverse series will be 75 displayed above the goods impaled upon the end blade of each transverse series. This will be better understood when it is stated that horizontal supports 5 are arranged, two 80 in each transverse series of blades, and that the said transverse supports 5 are interposed 85 between the central blade of each transverse series and the two blades at opposite sides of the central blade. Furthermore all of the central blades of the several transverse series are connected by longitudinal horizontal 90 supports 6. These longitudinal horizontal supports 6 are appropriately connected to the central blade comprised in the transverse series alluded to and they are arranged in about the same horizontal plane as the upper 95 ends of the intermediate blades of the said series. Thus goods impaled upon the central blades of each series will be supported by the bars 6 while the goods impaled upon the intermediate blades of the transverse series 100 will be supported by the horizontal transverse bars 5. Goods impaled on the end blades of each transverse series will be supported by the top of the support 2 and from this it will be readily understood that 105 the goods nearest the side edges of the table top or other support 1 will rest on said support 1, the goods on the next inner blades in the transverse series will be supported by the bars 5 and hence will be maintained in 110 spaced relation to the support 3, while the goods impaled upon the blades in the centers

of the transverse series will be supported by the bars 6 and hence will be caused to extend above all of the other bolts of goods in the transverse series. Manifestly the goods im-
5 paled upon the blades 3 at the ends of the device will be supported on the support or table top 1.

It will be apparent from the foregoing that in proportion to its size the specific embodiment disclosed is adapted to display to excellent advantage a large number of bolts of materials, and this in such manner that the dry goods is brought in front of the public and is displayed in substantially the same 10 manner as it would appear if embraced in a dress or other garment, and moreover all of the merchandise on my novel device is displayed so that by a glance at one side or one end of the device the effect of a plurality 15 of pieces may be readily ascertained by a prospective purchaser, and in the event of a purchaser selecting one of the pieces of material the bolt of material may be expeditiously and easily lifted from its blade and 20 then after the desired portion is cut from the bolt, the bolt may be as readily restored to position on the blade and draped to attract the attention of prospective buyers. 25

It will be appreciated from the foregoing 30 that the device will be practically advantageous when the uprights 3 and 4 are of a form or forms other than blades.

Manifestly when deemed expedient, the inventive idea disclosed herein may be extended throughout the area of a store, and notwithstanding it is feasible to make the device of wood, composition or other cheap material, the device as a whole is adapted to last for an indefinite period of time, this 35 because the display of the goods in the manner described subjects the device to practically no wear.

It will further be noted that the device is adapted to be economically fabricated, irrespective of the material or materials employed in its construction. 45

When deemed expedient the central blades of the transverse series in the embodiment illustrated may be braced by angle blocks 7 disposed at opposite sides of the blades and fixed thereto and also fixed to the support or table top 1, as shown in Figure 3.

I have explicitly described the construction and relative arrangement of the parts 50 embraced in the present embodiment of my

invention in order to impart a full, clear and exact understanding of the said embodiment. I do not desire, however, to be understood as limiting myself to the precise construction and relative arrangement as shown and described, my invention being defined by my appended claims within the scope of which modifications may be made without departure from my invention.

Having described my invention, what I 65 claim and desire to secure by Letters-Patent, is:—

1. A display device comprising a support, transverse series of spaced blade-like upwardly tapered uprights connected to and extending upwardly from said support, the central uprights of each series being longer than the other uprights in the series and the intermediate uprights in each series being shorter than the central upright and longer 75 and higher than the end uprights, transverse horizontal bars interposed between and fixed intermediate points of the central upright of each transverse series and the next adjacent uprights at opposite sides of said central upright, and longitudinal bars connected to and connecting the central uprights of the several transverse series at an intermediate point in the height of said uprights. 80

2. A display device comprising a support, transverse series of spaced blade-like upwardly tapered uprights connected to and extending upwardly from said support, the central upright of each series being longer 90 than the other uprights in the series and the intermediate uprights in each series being shorter than the central upright and longer and higher than the end uprights, transverse horizontal bars interposed between and fixed 95 to intermediate points of the central uprights of each transverse series and the next adjacent uprights at opposite sides of said central upright, and longitudinal bars connected to and connecting the central uprights 100 of the several transverse series at an intermediate point in the height of said uprights; the said support being also equipped at opposite ends of the several transverse series of uprights with end blade-like, upwardly 105 tapered uprights disposed at right angles to the other uprights.

In testimony whereof I affix my signature.

ZELTON D. BRUMBERG,
